(57) **CLAIM**

The ornamental design for a conical two-blade centrifugal pump impeller, as shown and described.

DESCRIPTION

FIG. 1 is a front, top, right side perspective view of a conical two-blade centrifugal pump impeller in accordance with the present invention;

FIG. 2 is a front view thereof;

FIG. 3 is a right view thereof, wherein the left view is the mirror image thereof;

FIG. 4 is a top view thereof;

FIG. 5 is a bottom view thereof; and,

FIG. 6 is a back view thereof.

The broken lines in the disclosure of FIGS. 1-6 are not considered part of the claimed design.
